RICHARD JOHN HARRINGTON HUDSON, OF PATNA, INDIA

FOLDING SEAT

Application filed May 10, 1929, Serial No. 362,092, and in Great Britain May 21, 1928.

This invention relates to folding seats of the kind which fold about a central vertical plane and constructed of rigid material such as wood or metal.

5 The primary object of the invention is to provide a folding seat comprising two seat members having hinged connection to each other, a side bracket member hinged to each seat member and a vertical support member hinged to each of said side bracket members.

10 A further object of the invention is to provide an improved folding seat having two seat members each having an opening therein providing a handle when collapsed, two bracket members each having a tapered end passing between an opening in each of said seat members, a hinge pin passing through the seat members and the tapered ends and a vertical hinge connecting the bracket members.

15 With these and other objects in view, the invention consists in the improved arrangement and combinations of parts hereinafter described in detail, the novel features of which are set out in the appended claiming clauses.

20 The invention is essentially applicable to a folding seat of rigid material such as wood or metal but the seat may if desired be constructed of two or more frames of rigid material and may have the centres or spaces inside the said frames filled by panels, interlaced cane, upholstery or any other material applicable to the construction of any ordinary seat.

25 The invention may be used in all cases in which a seat is required to fold in a vertical plane as in the case of seats provided in public or private places of assembly where a passage of passages in directions across or perpendicular to the lines or rows of seats are desirable and can be readily formed by folding the seats. The invention is also applicable to portable seats of various descriptions required to fold in a vertical plane and to the seats of stick seats and the like and is particularly applicable to the seats and thwarts of a folding or collapsible boat particularly those of the kind provided with a

rigid central keel or web to which the seats may be conveniently attached.

30 The invention is illustrated in two forms of execution in the accompanying two sheets of drawings which show the folding seats of a collapsible boat and the seat of a stick seat respectively; but it is to be understood that these are by way of example only, and that the invention can be readily applied to folding seats of other form and for other purposes than those illustrated in which a seat is required to fold into a vertical plane.

35 In the accompanying drawings, Sheet 1, Fig. 1 illustrates part of the plan of any form of boat in which it is desired to provide seats which will fold in the vertical central longitudinal plane of the boat showing seats designed in accordance with the invention fitted and erect.

40 Fig. 2 is the central sectional view of part of the boat showing the seats collapsed.

45 Figs. 3 and 4 illustrate the end or stern seat and thwart respectively and showing the seats in the position of (1) collapsed, (2) partly opened and (3) fully opened or erect.

50 Sheet 2 illustrates the invention applied to the seat of a stick seat.

55 Fig. 5 is a front elevation showing the seat collapsed and adopted as a convenient handle for carrying the stick.

60 Fig. 6 is an end elevation also showing the seat collapsed as in Fig. 5.

65 Fig. 7 illustrates the end elevation of the seat erected, and

70 Fig. 8 illustrates a plan of the seat erected.

75 Fig. 9 is a vertical section of the collapsed seat along the line AB,

80 Fig. 10 is a horizontal section of the collapsed seat along the line CD, and

85 Fig. 11 is a section along the line EF.

90 Turning now to Sheet 1 of the drawings the forms of seat illustrated comprise, the seat 1 hinged at the centre along the two parallel lines 2, each side of the seat being supported by a bracket 3 which is arranged to swing about a vertical hinge or pivot 4 attached to the sides of the central fixed web or abutment 5 which is formed by an upward rigid extension from the keel of the boat, each said

bracket being hingedly connected along its upper edge 6 to the under side of the seat.

The seats in their erect position illustrated in plan in Fig. 1 and in perspective view in Fig. 3 (3) and Fig. 4 (3) bear down upon the upper edge of the fixed web 5 which supports the centre of the seat, the sides of the seat being supported along diagonal lines by the upper edges of the swinging brackets 3 to which the seats are hingedly connected. Figs. 3 and 4 illustrate the manner in which the seats are erected or collapsed.

To erect the seat from the folded or collapsed position shown in Fig. 2 and in Fig. 3 (1) and Fig. 4 (1) the uppermost part of the centre of the seat is depressed or the brackets 3 may be swung outwards about their vertical hinges or pivots. Fig. 3 (2) and Fig. 4 (2) illustrate the connected movement of the seat and swinging brackets and show that as the brackets swing outwards the centre of the seat, hinging along the parallel lines 2 and the seat being hingedly connected to the brackets on its under side, falls and the lower corners of the seat fly outwards. A further downward depression of the uppermost part of the centre of the seat causes the centre of the seat to fall into complete contact with the upper edge of the fixed web 5 at the same time the brackets 3 swing outwards into their normal position when the seat is erect as illustrated in Fig. 1 and in Fig. 3 (3) and Fig. 4 (3).

The weight of a person sitting on the seat will maintain it in its erect position but if it is desired to fix the seat in its erect position a fastener of any suitable design may be provided at the centre of the front of the seat point 7.

For the sake of additional clearness arrows are shown in Fig. 1 to indicate the movement of the swinging brackets when the seats are being collapsed and in Fig. 2 to indicate the movement of the uppermost part of the centre of the seats when the seats are being erected.

Turning now to Sheet 2 of the drawings illustrating the invention as applied to a stick seat, the seat 1 is designed to combine lightness and strength and is of such form that when folded or collapsed as shown in Fig. 5, it forms a convenient handle by which the stick may be carried and when erect, Fig. 7 and Fig. 8, it forms a suitable seat supported on the stick.

The seat 1 is hinged along the line 2 which divides the seat symmetrically about its centre line. The two halves of the seat fold into contact when the seat is collapsed as shown in Fig. 5, and the halves being semi-circular in section at 11 a convenient hand grip is formed by which the seat is maintained in a collapsed position and by which the stick seat may be carried.

The two brackets 3 are arranged to swing about a common vertical pivot 4 mounted

upon the upper end of the stick. The upper edges of the said brackets 3 are formed into tapered bosses 6 which are drilled to receive the pins 8 which pass diagonally through and are screwed into the body of the seat thus forming hinged connections between the swinging brackets 3 and the seat 1 along the diagonal lines shown in the plan Fig. 8 of the seat erected and also in the horizontal section along C, D, Fig. 10 of the seat collapsed.

In the seat as designed the axes of the four hinges, namely, the common vertical pivot 4 on which the swinging brackets 3 are mounted, the seat hinge 2 and the two hinges connecting the swinging brackets to the seat by means of the pins 8 all maintain a common point of intersection in any position of the seat from fully collapsed to fully erected.

When the seat is collapsed as shown in Fig. 5 and Fig. 6 and in the sections, Fig. 9, Fig. 10 and Fig. 11, the swinging brackets 3 are accommodated between the two halves of the folded seat 1 by recessing parts of the underside of the seat between the points 9 and 10 also shown in broken lines in the plan of the seat erected Fig. 8. To enable the said parts of the underside of the seat to be recessed without undue weakening of the seat the upper surface of the seat protrudes outwards where recessing is necessary at the underside as shown in the end elevations Fig. 6 and Fig. 7 and in the sections Fig. 9, Fig. 10 and Fig. 11 and incidentally the shape of the seat when erect as shown in Fig. 7 and Fig. 8 is thereby improved as the centre of the seat is slightly depressed and the outer edge at the back of the seat is slightly raised.

To erect the seat from the folded or collapsed position Fig. 5, the grip of the hand at 11 is released and the two halves of the seat are drawn apart hinging about the centre hinge 2 and being supported upon the swinging brackets 3 which rotate outwards about the vertical pivot 4.

The seat is finally erected by a depression and downward movement of the centre of the seat until the stops 12 on opposite sides of the centre hinge, 2, come into contact and arrest the further downward movement of the centre of the seat when the seat is erect as shown in Fig. 7 and Fig. 8.

Obviously the invention is not limited to the precise forms of construction illustrated in the drawings as the form of construction will be subject to the purpose for which the seat is required and the position which it is required to occupy.

So far as I am aware, however, it has not previously been proposed to construct a folding seat of solid material such as wood or metal which is capable of folding in a vertical plane in the manner described, and the invention is to be interpreted broadly as covering any forms of construction which fall within the ambit of the appended claims.

I claim:—

1. A folding seat comprising in combination two seat members having hinged connection to each other, a side bracket member hinged to each seat member and a vertical support member hinged to each of said side bracket members.
2. A folding seat comprising in combination a vertical support, two bracket members connected to said vertical support by hinge means having movement about a vertical axis, a seat member connected to each said bracket member by a hinge having movement about a horizontal axis intersecting the vertical axis of the first-mentioned hinge means and hinge means connecting the two said seat members.
3. A folding seat comprising in combination a vertical support, two bracket members connected to said vertical support by hinge means having movement about a vertical axis, a seat member connected to each said bracket member by a hinge having movement about a horizontal axis intersecting the vertical axis of the first-mentioned hinge means and hinge means connecting the two said seat members.
4. A folding seat comprising, in combination, two seat members, each having an opening therein providing a handle when collapsed, two bracket members, each having a tapered end passing in an opening in each of said seat members, a hinge pin passing through said seat members and said tapered ends, and a vertical hinge connecting said bracket members.
5. A folding seat comprising, in combination, two seat members formed with recesses on their under sides, two bracket members, one pivoted to each said seat member and being housed when in the collapsed position of the seat inside the recesses formed in the seat members, and a support member, said support member being connected to each of said bracket members by hinge means movable about a vertical axis.
6. In a boat, a rigid, longitudinally ranging abutment, a folding seat connected to said abutment and including seat members supported from the abutment and extending on opposite sides thereof in seat-forming relation when extended, and means whereby the seat members when folded are arranged in planes parallel with the abutment.
7. In a boat, a rigid, longitudinally ranging abutment, a folding seat connected to said abutment and including seat members supported from the abutment and extending on opposite sides thereof in seat-forming relation when extended, and means whereby the seat members when folded are arranged in planes parallel with the abutment, said means providing supports for the seat members when in seat-forming relation and operating to move the seats from edge relation in folded

position to seat-forming relation in extended position.

8. In a boat, a rigid, longitudinally ranging abutment, a folding seat connected to said abutment and including seat members supported from the abutment and extending on opposite sides thereof in seat-forming relation when extended, and means whereby the seat members when folded are arranged in planes parallel with the abutment, said means including a bracket member hinged to the under side of each seat member and mounted on the abutment for swinging movement in a substantially horizontal plane.

In testimony whereof I affix my signature. 80
RICHARD JOHN HARRINGTON HUDSON.
